Abe J. Gaines, Glencoe, Ill., assignor to Saginaw Furniture Shops, Inc., Chicago, Ill., a corporation of Michigan

Application March 29, 1954, Serial No. 29,751

Term of patent 14 years

(Cl. D33—19)

Fig. 1.

Fig. 2.

Figure 1 is a perspective view of a combined buffet and extension table embodying my new design.

Fig. 2 is a perspective view illustrating the buffet open and the table element in an extended position.

The salient features of the design are most clearly delineated in that aspect of the invention appearing in Fig. 2.

I claim:

The ornamental design for a combined buffet and extension table, substantially as shown and described.
